UNITED STATES PATENT OFFICE

LEON BOCK, OF NEW YORK, N. Y., ASSIGNOR TO SAMUEL WEIN, OF NEW YORK, N. Y.

DESIGN FOR A RING

Application filed December 17, 1926. Serial No. 42,127. Term of patent 7 years.

To all whom it may concern:

Be it known that I, LEON BOCK, residing at #960 East 163rd Street, in the borough of Bronx, city and State of New York, have invented a new, original, and ornamental Design for Rings, of which the following is a specification, reference being had to the accompanying drawing, forming part hereof.

The figure is a perspective view of a ring showing my new design. The ornamentation on the opposite outer portion of the ring is a repetition of that shown.

I claim:

The ornamental design for a ring, as shown and described.

LEON BOCK.

CERTIFICATE OF CORRECTION.

Design Patent No. 86,591.

Granted March 29, 1932, to

LEON BOCK.

It is hereby certified that error appears in the above numbered patent requiring correction as follows: In the heading to the printed specification and drawing, date of filing, for "December 17, 1926" read December 17, 1931; and that the said Letters Patent should be read with this correction therein that the same may conform to the record of the case in the Patent Office.

Signed and sealed this 17th day of May, A. D. 1932.
